UNITED STATES PATENT OFFICE.

HENRY O. LOEBELL, OF MALBA, NEW YORK, ASSIGNOR TO COMBUSTION UTILITIES CORPORATION, OF NEW YORK, N. Y., A CORPORATION OF MAINE.

GAS-FIRED FURNACE HAVING TILE BURNERS.

Application filed January 5, 1927. Serial No. 159,034.

This invention relates to improvements in means for burning combustible gaseous mixtures.

The principal object of the invention is to provide a burner which of itself shall constitute a source of radiant heat. Another object of the invention is to provide a burner of such construction that it may serve as a combined heating element and wall of a furnace.

Another object of the invention is so to construct a burner of the character indicated that it can be built up from a plurality of similar tile members.

The invention also embodies other objects as will hereinafter more fully appear in the detailed description of the invention.

Referring to the drawing wherein the preferred form of the invention is shown:

Fig. 1 is a vertical sectional view through a regenerative furnace showing the roof as embodying the burner of the present invention;

Fig. 2 is a sectional view of the furnace taken of line 2—2 of Fig. 1;

Fig. 3 is an end elevation of one form of tile members from which the burner may be constructed;

Fig. 4 is a side elevation of the tiles shown in Fig. 3;

Fig. 5 is a plan view of a modified form of burner surface;

Fig. 6 is a section taken on line 6—6 of Fig. 5 and showing the preferred form of tiles from which a burner of the type shown in Fig. 5 may be built up; and

Fig. 7 is an elevation with parts in section of tile members shown in Figs. 5 and 6.

The invention has been shown as embodied in a forge furnace of the regenerative type wherein the hearth is indicated at 10, the roof at 12 and the regenerators at 14, the roof being built up from tiles constructed in accordance with the present invention.

The manner of suspending the tiles forms no part of the present invention. As shown in the drawings the tiles are notched as at 16, to permit them to be hung on the transverse tie bars 18 of the furnace.

The improved burner is constructed to provide a wall-like surface provided with a plurality of outwardly-flaring, relatively shallow pits wherein a combustible gaseous mixture may be burned for the purpose of heating the walls of the pits to incandescence

and thus constitute them sources of radiant heat. The combustible mixture is introduced into the bottom of the pits through passages formed in the burner wall. The burner surface is preferably built up from a plurality of like ends of similar tiles which are preferably rectangular in cross-section above said ends in order that a burner surface or wall of the desired area may be easily and cheaply built up.

For illustrative purposes the form of burner surface shown in Figs. 3 and 4 has been shown as constituting the roof of the furnace.

Like reference characters refer to similar parts throughout the several views.

In Figs. 3 and 4 the tiles are shown as provided with wedge-shaped ends whereby when they are arranged alongside each other a trough or pit 20 is formed. The sides of the tile for a short distance above the sides of the wedge are indented to provide a narrow feed passage 22 and main supply passage 24 for the combustible mixture which is to be burned in the pits. The feed passage 22 in this form of the invention is coextensive with the length of the trough or pit but it is within the spirit of the invention to make the feed passage non-continuous, that is to say, as a series of holes leading from the supply passage 24 to the bottom of the trough or pit. The form of tiles shown in Figs. 3 and 4 can be manufactured at relatively small expense and ordinarily will constitute the preferred form of tiles to be used in building up the burner surface.

Figs. 5, 6 and 7 collectively show a tile construction which embodies the essential characteristics of the already described form of tile, that is to say, it embodies a pitted surface and passages in the tiles by means of which the combustible mixture is supplied to the bottom of the pits for burning. In this particular construction, however, each tile is formed to provide a four-sided pit in an end thereof whereby the burner surface comprises a series of non-continuous pits as distinguished from alined pits communicating with each other at their ends as in the construction shown in Figs. 3 and 4. However, the main supply passage 24 in the individual tiles communicate with each other as in the other construction. The combustible mixture is entered into the pits through individual passages or ports 22 leading from

the supply passage 24 as will be now readily understood.

In accordance with the present invention the combustible mixture is an explosive gaseous mixture. A mixture of such composition will burn in the absence of air in the pits and provide maximum heat in the pits with the result that the pit walls will become glowing hot and serve as sources of radiant heat which will be radiated onto the work to be heated by reason of the flaring side walls.

10 The depth of the pits is an important factor to satisfactory operation, the best results being obtained when the angle included between the pit walls is in the neighborhood of 90°. The tiles are preferably made from a refractory material which is a poor conductor of heat thereby making it practicable to build a furnace wall and burner as a unit.

15 As already indicated, burners constructed in accordance with the present invention are particularly well adapted for use as a combined heating element and furnace wall or roof in various type of furnaces. In the present application the burner has been shown as constituting the roof of a regenerative forge furnace. The burner tiles are suspended over the hearth 10 in any suitable manner or as shown. If the pits are in the form of a continuous trough, the gaseous mixture is conveniently introduced at one end of the alined tile conduits 24 as by means of a tube or pipe 26 extending through a 20 side wall of the furnace, each pipe being provided with a controlling valve 28. When the burner is to be used in a regenerative furnace the burner is preferably divided into two banks of equal area by a dividing wall 32 and the banks alternately fired. Assuming that the right hand bank is to be fired, hot air from the right hand regenerator 14 is led upwardly through a passage 34 and discharged into the stream of gas flowing 25 toward the tile conduit 24, a damper 36 being provided in the passage 34 to regulate the air supply. A gate 38 in the furnace wall adjacent the burner at the left hand side of the furnace controls the flow of the 30 products of combustion to the left hand regenerator 14. When the left hand burner bank is fired the left hand gate is closed and the right hand gate 38 opened as will now be readily understood. The work-door passage 35 into the heating chamber is indicated at 40.

The burner can also be used in connection with a recuperator furnace by firing only every other trough the intermediate troughs serving as an outlet for the combustion products it being understood that the outlet end 60 of such trough will be connected with a passage leading directly to the recuperator.

What is claimed is:

1. A combined wall and burner having a surface comprised of a plurality of like ends 65 of similar tiles, said ends being formed to constitute a series of outwardly-flaring, relatively shallow pits, and passages in the tiles opening on the bottom of the pits, said passages constituting conduits through which a 70 combustible gaseous mixture may be introduced into said pits.

2. A combined wall and burner having a surface comprised of a plurality of like ends 75 of similar tiles, said end being formed to 80 constitute a series of outwardly-flaring, relatively shallow pits, and alined passages in the tiles opening on the bottom of the pits, said passages constituting conduits through which a combustible gaseous mixture may be 85 introduced into said pits.

3. In a heating chamber, the combination of a combined roof and burner having an inner surface provided with a plurality of outwardly-flaring relatively shallow pits, 85 and passages in the roof in open communication with the bottom of the pits through which a combustible gaseous mixture may be introduced into the pits.

4. In a heating furnace, the combination 90 of a combined burner and roof having an inner surface provided with a plurality of outwardly-flaring, relatively shallow pits, means dividing the pits into two independent banks, independent passages for each 95 bank in open communication with the bottom of the pits through which a combustible gaseous mixture may be introduced into the pits, a plurality of checker-work means through which the products of combustion 100 and air may be alternately passed, means permitting the banks to be alternately fired, and gates opposite the fired bank through which the products of combustion may pass to one of said checker-work means for heating it, and means for controlling the flow 105 of heated air from the other of said checker-work means to the burner bank being fired.

In testimony whereof I affix my signature.

HENRY O. LOEBELL.
